UNITED STATES PATENT OFFICE.

PASCHAL L. BOTTOMS, OF AMARILLO, TEXAS.

SCAFFOLD.

Application filed August 27, 1927. Serial No. 215,851.

This invention relates to improvements in scaffolds adapted to be used by masons, painters and the like, and has particular reference to a scaffold of this kind having improved means whereby it may be raised by persons within or upon the framework of the building.

A further object of the present invention is to provide a device of the above kind having a minimum number of operating parts and embodying such simple and durable construction as to meet with the requirements for a successful commercial use.

A still further object is to provide means whereby the platform of the scaffold may be readily leveled transversely preparatory to raising the same.

Other objects will become apparent as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views;

Figure 1 is a diagrammatic side elevational view of the framework of a building, with a scaffold constructed in accordance with the present invention mounted thereon.

Figure 2 is a front elevation of the device shown in Figure 1.

Figure 3 is a plan view, partly broken away, of one of the hoisting devices employed in the scaffold shown in Figures 1 and 2.

Figure 4 is a side elevational view of the device shown in Figure 3.

Figure 5 is a vertical section on line 5—5 of Figure 4.

Figure 6 is an enlarged detail section on line 6—6 of Figure 4.

Figure 7 is a vertical section on line 7—7 of Figure 4.

Figure 8 is a vertical section on line 8—8 of Figure 4.

Figure 9 is an enlarged detail section on line 9—9 of Figure 3, and

Figure 10 is an enlarged perspective view of one of the members for preventing accidental lateral shifting of the operating shaft for the winding drums.

Referring more in detail to the drawings, 5 indicates the framework of a building, and suspended at each end from the

top of the building by means of a hoisting device is a scaffold platform 6.

As the hoisting devices are alike, description of one will suffice for both. As shown, each hoisting device embodies a frame composed of a pair of beams 7 rigidly connected in spaced parallel relation, as at 8, and preferably consisting of channel beams with inwardly projecting flanges. This frame is suitably secured, as at 9, to the top of the building so as to project a distance beyond the front of the latter, and secured at their lower ends to the outer sides of the inboard ends of the beams 7 are spaced pairs of uprights 10 and 11 in the upper ends of which are journaled the shafts of winding drums 12 and 13. These drums have pairs of similar end spur gears 14 and 15 engaged by pawls 16 and 17 whereby the drums may be freely turned in one direction but will be prevented from turning in the opposite direction unless the pawls are released. As shown, the pawls are rigid with transverse horizontal operating shafts respectively journaled in extensions 18 of the uprights 10 and in uprights 19 secured to the beams 7 outwardly of drum 13.

A further pair of uprights 20 are secured to the beams 7 between the uprights 10 and 11, and slidably and rotatably mounted in the upper ends of these uprights 20 is a shaft 21 having end operating cranks 22 and on which are secured elongated spur pinions 23 arranged between and adapted to simultaneously mesh with the gears 14 and 15. The uprights 10 are laterally offset in one direction as shown in Figures 3 and 7, while the uprights 11 are offset in the other direction, as shown in Figures 3 and 8, thus positioning the gears 14 and 15 out of alignment. The uprights 20 are, however, laterally offset away from each other as shown in Figures 3 and 5, thus leaving spaces between the same and the pinions 23 when the latter are engaged with the gears 14 and 15, whereby the shaft 21 may be slid laterally of the beams 7 to disengage the pinions 23 from the gears 14 while remaining engaged with gears 15 or to disengage them from gears 15 while remaining engaged with gears 14. In this way, either winding drum may be disconnected or freed from the operating shaft and the other drum for independent actuation, thus enabling any slack to be taken up in either of the

cables 24 or 25 for transversely leveling the scaffold platform 6 preparatory to raising the latter. The cable 24 is attached to drum 12 and passes outwardly over a guide 5 pulley 26 supported by uprights 27 attached to the outboard ends of the beams 7, the lower ends of the cable 24 being attached to the outer side of platform 6. In a like manner, cable 25 is attached to the drum 13 10 and the inner side of platform 6, the same passing over a guide pulley 28 supported by shorter uprights 29 secured to the beams 7 inwardly of the uprights 27. It is thus apparent that by turning shaft 21 with 15 pinions 23 engaging gears 14 and 15, both drums may be turned at a corresponding speed to wind the cables 24 and 25 thereon and raise the end of the scaffold platform while preserving the transverse level of the 20 latter. A corresponding operation of the other hoisting device for the other end of the platform will result in raising the latter while preserving its level longitudinally.

If desired, suitable releasable means may 25 be provided to prevent accidental longitudinal shifting of shaft 21 transversely of the frame when pinions 23 are in engagement with gears 14 and 15, and such means is shown as embodying chock members 30 30 pivoted to the uprights 20 and adapted to be swung to or from between the pinions 23 and the uprights 21, the chock members 30 being slotted, as at 31, to fit over shaft 21 when operatively disposed and having suitable handles 32. If desired, the shafts 21 of 35 the two hoisting devices may be coupled for causing the operation of one hoisting device by the other.

As shown better in Figures 4 and 6, the 40 platform 6 may embody boards laid across end transverse beams 33 and held together between the cables 24 and 25 as well as held down by cross plates 34 disposed across the upper surfaces of the boards. The cables are 45 passed through the ends of the plates 34 and anchored to the adjacent ends of the beams 33, as at 35.

In operating the device to lift the platform, the cranks 22 are turned, thereby imparting rotation simultaneously at the same rate of speed to the drums 12 and 13 and winding up the two cables at the same rate so that the platform will not be laterally tilted. Moreover, the operation may be 55 conducted by a person standing upon the building and without the necessity of leaning into a dangerous position.

Minor changes may be made without departing from the spirit and scope of the 60 invention as claimed.

What I claim as new is:

1. In a scaffold, a support, a pair of winding drums mounted on said support and disposed in laterally offset relation, spur

gears on the ends of said drums, a shaft 65 journaled between the drums and having pinions adapted to simultaneously mesh with the gears of both drums, said shaft being slidably transversely of the support to selectively disengage the pinions from the 70 gears of either drum, cables attached to said drums and adapted to be attached to a platform at the inner and outer sides thereof, said support embodying a frame, and two pairs of uprights attached to the inboard end of the frame and each having one of the 75 drums journaled thereon, said pairs of uprights being laterally offset in opposite directions.

2. In a scaffold, a support, a pair of winding drums mounted on said support and disposed in laterally offset relation, spur gears on the ends of said drums, a shaft journaled between the drums and having pinions adapted to simultaneously mesh with the gears of both drums, said shaft being slidably transversely of the support to selectively disengage the pinions from the 80 gears of either drum, cables attached to said drums and adapted to be attached to a platform at the inner and outer sides thereof, said support embodying a frame, and two pairs of uprights attached to the inboard end of the frame and each having one of the 85 drums journaled thereon, said pairs of uprights being laterally offset in opposite directions, and a further pair of uprights attached to the frame and having said shaft mounted thereon, the last named uprights being laterally offset away from each other 90 to permit sliding of said shaft.

3. In a scaffold, a support, a pair of winding drums mounted on said support and disposed in laterally offset relation, spur gears on the ends of said drums, a shaft journaled between the drums and having pinions adapted to simultaneously mesh with the gears of both drums, said shaft being slidably transversely of the support to selectively disengage the pinions from the 95 gears of either drum, cables attached to said drums and adapted to be attached to a platform at the inner and outer sides thereof, said support embodying a frame, and two pairs of uprights attached to the inboard end of the frame and each having one of the 100 drums journaled thereon, said pairs of uprights being laterally offset in opposite directions, and a further pair of uprights attached to the frame and having said shaft mounted thereon, the last named uprights being laterally offset away from each other 105 to permit sliding of said shaft and chock members pivoted to the last named uprights and positionable in the path of the pinions to hold 110 the shaft from sliding.

In testimony whereof I affix my signature.

PASCHAL L. BOTTOMS.
